UNITED STATES PATENT OFFICE.

DON C. WALKER AND BONZANO WEEKS, OF MEMPHIS, TENNESSEE.

KEY-CONTROL TELEPHONE SWITCH.

1,424,863.

Specification of Letters Patent. Patented Aug. 8, 1922.

Application filed September 26, 1921. Serial No. 503,407.

To all whom it may concern:

Be it known that we, DON C. WALKER and BONZANO WEEKS, citizens of the United States, and residents of Memphis, in the 5 county of Shelby and State of Tennessee, have invented certain new and useful Improvements in Key-Control Telephone Switches, of which the following is a specification.

10 This invention relates to telephone equipment, and is particularly designed for use in connection with isolated telephone stations, such as are provided along a railway track for the convenience of trackmen and other 15 employees in communicating with headquarters. Telephone installations of this character are peculiarly liable to injury by lightning and, because of their isolated locations, are subject to use by unauthorized 20 persons with consequent complications which might easily, in some cases, lead to disastrous results.

The object of our invention, therefore, is to provide a simple and efficacious device for 25 protecting telephone installations, of the kind referred to, from high potential electrical discharges and from unauthorized use. To this end, we provide a normally open gap in the substation circuit of sufficient 30 electric strength to withstand high potential atmospheric discharges, and for closing this gap we provide a key of a particular construction, thus rendering it impracticable for unauthorized persons to close the circuit and 35 thereby preventing unauthorized use of the instruments.

Referring to the accompanying drawings, Figure 1 is a perspective view of a casing in which the sub-station equipment is housed,

40 Figure 2 is a top plan view of the normally open switches in the sub-station circuit and operating mechanism therefor,

Figure 3 is a rear elevation of Figure 2,

Figure 4 is a vertical longitudinal section 45 thereof,

Figure 5 shows a side and end view of a key adapted to operate the device and

Figure 6 shows a key guide.

Figure 1 shows an ordinary sub-station 50 box for housing the transmitting and receiving instruments and their accessories. Supported in this box in any suitable manner is a frame consisting of side plates 2 connected by cross rods 3. Attached to the frame is a 55 horizontal shelf 4 on which are screwed two pairs of spring terminals 5. The members

of each pair are normally out of contact as shown in Figure 4, being spaced by suitable insulating material. These terminals form a normally open gap in both of the conductors 60 constituting the substation circuit and hence the telephone cannot be used until said terminals have been moved into contact.

Pivoted on a cross rod supported by the frame is a lever 7 and attached to the free 65 end thereof is a block of insulating material 8 extending across and below the free ends of the lower spring terminals, the downward movement of the lever being limited by a cross rod 9. The lever has a curved surface 70 10 formed intermediately thereof for cooperation with a key, as will be described presently. Extending transversely of the frame and attached thereto in any suitable manner is a tubular member 11, having its axis parallel with and located somewhat above the axis of said curved surface 10, the tubular member extending through the side 2 of the frame and registering with a key bushing defining a key hole in the side of the sub-station box. 75 As clearly shown in Figure 6, the tubular member 11 has a longitudinal slot 12 extending about halfway thereof and terminating in a wider circumferential slot 13. Supported axially of the member 11 is a stem 14 with 80 its free end located in the key hole of the box. Figure 5 illustrates a type of key which may be used for operating the device. As shown, this key is of the ordinary barrel type having a barrel adapted to receive the 85 stem 14 and a prong adapted to slide in the longitudinal slot of the tubular member and to rotate in the circumferential slot thereof.

To operate the device, one must have a key 90 of the particular construction for which the device is designed. When desirous of communicating with the central station or headquarters, one having such a key inserts it in the key hole at the side of the box until the tongue registers with slot 13, in which position the key can be turned to engage the curved surface 10 which being eccentric to the axis of the key, causes the tongue, when turned, to raise the lever and press the lower spring terminals into firm contact with the 95 upper terminals, closing the circuit and producing a calling signal at the central station. It is necessary to hold the key in circuit closing position during the calling operation and subsequent conversation, for when released 100 the key is returned and the circuit opened by the spring action of the contacts. This, we 105

regard, as an important advantage of the device, as it precludes the possibility of the circuit being accidentally left closed.

It will be understood that since the stations to which our invention is adapted to be applied are never called from the central station, it is possible to have a normally open substation circuit without in any way impairing the usefulness of the station.

10 Having particularly described the structure and mode of operation of our invention, what we claim as new and desire to secure by Letters Patent is:—

1. In a substation telephone equipment, a box for housing the receiving and transmitting instruments, a frame secured in said box, two pairs of insulated leaf springs, the members of each pair being supported on said frame in spaced superposed relation and being connected in the substation circuit so as to form a pair of normally open gaps therein of sufficient dielectric strength to withstand high potential atmospheric charges, a lever fulcrumed on said frame having an insulating block fixed on its free end and extending under the end of the lower member of each pair of said leaf springs, said lever having a curved surfaced formed on the lower side thereof, a tubular member supported transversely of said frame beneath said lever and having a longitudinal slot and a circumferential slot communicating with the inner end thereof and located opposite the curved surface of said lever, the axis of said tubular member being parallel with and somewhat above the axis of said curved surface, and a stem fixed axially of said tubular member, said box having a key hole in registry with said tubular member for insertion of a key of the barrel type.

2. In a substation telephone equipment, a box for housing the receiving and trans-

mitting instruments, a frame secured therein, two pairs of spring contact terminals supported in said box, the members of each pair being supported on said frame in spaced superposed relation and being connected in the substation circuit so as to form a pair of normally open gaps therein of sufficient dielectric strength to withstand high potential atmospheric charges, a lever having an insulating block fixed on its free end and extending under the free end of the lower member of each pair of said spring terminals, and a key guide extending beneath said lever and in registry with the key hole in said box.

3. In a substation telephone equipment, a box for housing the receiving and transmitting instruments, two pairs of spring contact terminals supported in said box, the members of each pair being supported in spaced relation and being connected in the substation circuit so as to form a pair of normally open gaps therein of sufficient dielectric strength to withstand high potential atmospheric charges, and key operated mechanism for holding said spring terminals into engagement, said spring terminals returning said mechanism to normal position when the key is released for the purpose described.

4. A switch for closing an electric circuit, comprising spaced terminals adapted to yieldingly resist movement for bringing the same together to establish the circuit, a lever for moving said terminals into engagement, and a key operated mechanism adapted to move said lever to bring the terminals together and also adapted to permit the lever to return to its initial position when released and thereby opening the circuit.

DON C. WALKER.
BONZANO WEEKS.
